SINK, WASHBASIN, AND THE LIKE

Jacques Stanitz, Warren, Ohio, assignor to The
Youngstown Pressed Steel Company, Warren,
Ohio, a corporation of Ohio

Application July 3, 1933, Serial No. 678,823

10 Claims.

(Cl. 4—187)

The invention relates to sinks, wash basins and the like formed from sheet or plate metal and preferably covered by a protective coating, such as an enamel coating. More particularly, the invention relates to such products in which a fluid receiving bowl, together in some cases with one or more drain boards, terminates in a rolled rim and a comparatively high splash-back lying in a plane substantially at right angles to the plane of the top of the rolled rim, and are all formed in and from a single piece or blank of sheet or plate metal.

Enamel coated cast metal sinks and the like have been made, but the same, particularly in large sizes, are very heavy and require two or three men to handle the same in installing such sinks; and frequently the larger sizes require legs to prevent sagging or to prevent undue strain upon the wall where they are installed.

Sheet metal enamel coated sinks have heretofore been made in which the bowl portion and a high splash-back therefor are either bolted or welded together. However, the appearance of such sinks is objectionable either because of the exposure of bolt heads, or because of the difficulty of making a satisfactorily welded joint without having the same more or less noticeable after being enameled.

Sheet metal sinks have also been made in which the bowl is surrounded by a rolled rim and is provided with a high upstanding splash-back, all formed from a single sheet of metal. However, such sinks have always been provided with notches or openings at the place where the ends of the rolled rim meet the splash-back, in order that the splash-back could be moved to an upright position by a bending operation, after which the cut edges of the slits or notches at the ends of the rolled rim, are welded together where the rolled rim meets the splash-back.

Such notching, slitting and welding operations are not only expensive, but the welded joint, in having a curved and recessed contour where the rolled rim ends and the splash-back meet, are always more or less noticeable and are difficult to cover with a satisfactory enamel coating having the same properties as the enamel coating on the remainder of the sink.

Moreover, when extremely long sinks are made, as when they are provided with a drain board at one or both sides of the fluid receiving bowl, or when large fluid receiving bowls are provided, the plane of the upright splash-back has always been located substantially continuous with the plane of the rear fluid receiving bowl wall; and it

is difficult to maintain a truly plane surface for the splash-back when subjecting the sink to heat for enameling the same, since the unequal strains imposed upon the splash-back during the forming operations may cause a slight warpage or weaving of the splash-back when the same is heated in the enameling furnace.

Accordingly, it is an object of the present invention to provide an improved construction for sinks, wash basins and the like, which overcomes the difficulties which have resulted in prior sink construction.

Furthermore, it is an object of the present invention to provide a sink and the like, in which a fluid receiving bowl, together in some cases with one or more drain boards, terminates in a rolled rim and in a comparatively high splash-back, and are all formed in and from a single piece or blank of sheet or plate metal without performing any notching and/or subsequent welding operations at the place where the rolled rim ends merge with the splash-back.

It is likewise an object of the present invention to provide a stiffening ledge at the top rear edge of the bowl of such a sink formed from a single piece or blank of sheet or plate metal, which stiffens the splash-back, and enables the splash-back to be maintained in proper position without warping, weaving and the like when the sink is subjected to heat for carrying out an enameling operation.

A further object of the present invention is to provide, in such sink constructions, a fluid receiving bowl having straight side walls, that is with the bottom thereof just as large as the top, to provide a maximum capacity for the fluid receiving bowl.

It is likewise an object of the present invention to provide sinks of such improved character, which may be readily coated with a preferably acid resisting enamel coating of the highest quality, so that the resulting coating is absolutely uniform in appearance and characteristics throughout, and which enamel coating is not weakened at any of the working surfaces of the sink due to previous operations in forming the sink prior to being enameled.

And finally, it is an object of the present invention to provide sinks incorporating the above described desiderata, which are very light in weight by being formed from sheet or plate metal, which are formed from a single blank of metal, and which are inexpensive to manufacture and have a pleasing and attractive appearance.

These and other objects may be obtained by the

constructions, arrangements, combinations, elements and formations, hereinafter described in detail and claimed, preferred embodiments of which are shown in the accompanying drawing, 5 which may be stated in general terms as including in a sheet metal sink having a fluid receiving bowl preferably with substantially upright side walls, and in some cases having one or more adjacent drain boards, the bowl and drain boards 10 terminating in a rolled rim and in an upright splash-back, all formed integrally from a single sheet of metal; a preferably laterally continuous stiffening ledge preferably substantially S-shaped in cross section formed between and merging into 15 the bowl and splash-back to provide an offset thereat, and in case drain boards are provided adjacent to the fluid receiving bowl, a portion of said ledge extending between and merging into the drain boards and splash-back; the rolled rim 20 being preferably continuous and surrounding the front and sides of said bowl and drain boards if used, the ends of the rolled rim terminating at and merging into said splash-back, the places of merger between the ends of the rolled rim being 25 seamless, and the line of intersection between the ledge and splash-back lying in the plane of the upper portion of the rolled rim.

In the drawing,

Figure 1 is a perspective view of a sink embodying the improved constructions;

Fig. 2 is a perspective view of a sink, similar to that shown in Fig. 1, embodying the improved constructions, but including a drain board at each side of the fluid receiving bowl;

Fig. 3 is a perspective view of a sink embodying the improved constructions, similar to that shown in Fig. 1, but including a short skirted rolled rim;

Fig. 4 is a perspective view of a sink, similar to that shown in Fig. 3, embodying the improved constructions, and including only a fluid receiving bowl;

Fig. 5 is an enlarged plan view of the improved sink shown in Fig. 1;

Fig. 6 is a transverse sectional view of the improved sink shown in Figs. 1 and 5, taken on the line 6—6, Fig. 5, certain sectional portions thereof being illustrative of the sink constructions shown in Figs. 2, 3 and 4;

Fig. 7 is an enlarged fragmentary sectional view taken on the line 7—7, Fig. 5;

Fig. 8 is an enlarged fragmentary sectional view taken on the line 8—8, Fig. 5; and

Fig. 9 is an enlarged fragmentary sectional view taken on the line 9—9, Fig. 7.

Similar numerals refer to similar parts throughout the various figures of the drawing.

Referring to Figs. 1 and 5 to 9, inclusive, the improved sink shown therein may include a fluid receiving bowl 10, having a bottom wall 11 provided with a drain opening 12, and having substantially upright or vertical walls, preferably substantially rectangular in cross section and including a front wall 13, a rear wall 14 and side walls 15, with preferably rounded corner walls 16 therebetween.

A drain board 17 preferably provided with a multiplicity of parallel grooves 18 set closely together, is preferably located adjacent to the fluid receiving bowl 10, and the drain board 17 preferably slopes slightly downward toward the bowl 10 as best shown in Fig. 8.

The bowl 10 and drain board 17 preferably terminate in a preferably continuous rolled or

turned rim 19 and in a vertical splash-back 20 preferably lying in an upright plane.

For the purposes of the present invention, the fluid receiving bowl 10, the drain board 17, the rolled rim 19 and the splash-back 20 are all 5 formed integrally from a single sheet of metal; and may be preferably made in accordance with the method set forth in my copending application entitled Process of making sinks, wash basins and the like, filed December 7, 1932, Serial No. 646,207, 10 matured as Patent No. 1,916,910, dated July 4, 1933.

The outer portion of the rolled rim 19 may be preferably integrally extended downward to form a long skirt 21 surrounding the fluid receiving 15 bowl 10 and drain board 17, as best shown in Figs. 1 and 6; or the rolled rim 19 may terminate in a short skirt 21a, as shown in Fig. 3.

The ends or end portions 22 of the rolled rim 19 terminate at and merge into the splash- 20 back at 23; and a stiffening preferably continuous, ledge, generally indicated at 24, is formed between and merges into the rear bowl wall 14, the drain board 17 and the splash-back 20. The present invention involves particularly the improved construction of the sink at the places 23 and of the ledge 24.

The provision of the stiffening ledge 24, which is preferably parallel with the rear bowl wall 14, offsets the plane of the bowl wall 14 from the 30 plane of the splash-back 20 and thereby provides an offset at the place where the ledge 24 merges into the bowl and splash-back; and the ledge 24 is preferably substantially S-shaped in cross section, and slopes generally rearwardly up- 35 wardly from the bowl to the splash-back, as best shown in Fig. 9, and may comprise a curved portion 24a merging into the bowl wall 14, and a flattened portion 24b, which merges into or intersects with the splash-back along a line 25, which 40 line extends between the places 23 and lies in the plane of the upper portion of the rolled rim, as best shown in Figs. 6 to 9, inclusive.

As stated, the splash-back projects upwards 45 from the rear of the fluid receiving bowl 10 and since the intersection of the same with the ledge portion 24b is the line 25, which line also passes through the places 23, the splash-back 20 may be originally formed horizontal in a one-piece sheet blank along with the bowl 10 and rolled rim 19, 50 and may thereafter be bent to the upright position shown, along the line 25, without having to notch the sheet blank around the places 23. The places 23, where the ends of the rolled rim 19 merge with the ends of the ledge line 25 and with the splash-back, are therefore seamless, and need 55 not be welded.

The drain board 17 is spaced below the plane of the upper portion of the rolled rim 19, which 60 passes through the line 25, so that a fluid dropping to the drain board will flow along the same into the fluid receiving bowl in the usual manner.

The location of the ledge 24 and its substantial- 65 ly S-shape, together with the offsetting of the splash-back 20 from the rear wall 14 of the bowl 10 materially stiffens the sink and the splash-back 20 so that the correct location of the splash-back may be maintained in a vertical plane without warping or weaving out of true when the 70 sink is subjected to heating in an enamel furnace for providing a preferably acid resisting vitreous enamel coating thereon.

Likewise, the fact that the places 23 where the 75 ends of the rolled rim 19 merge with the splash-

back 20 are seamless and need not be welded, enables the improved sinks to be inexpensively made and enables a uniform enamel coating to be provided on the sink especially at the places 23. 5 Thus, the present improvements provide a very light weight sink formed from a single blank of metal which is inexpensive to manufacture, has a pleasing and attractive appearance, and is very strong in use.

10 The construction shown in Fig. 2, is identical in all respects with that shown in Fig. 1, excepting only that a left-hand drain board 17a is provided, similar in all respects to the right-hand drain board 17; and the splash back 20b extends in back 15 of the fluid receiving bowl and both drain boards 17 and 17a.

The construction shown in Fig. 3, is similar to or identical with the construction shown in Fig. 1 in all respects excepting only that the rolled rim 20 terminates in a short skirt 21a.

The construction shown in Fig. 4, is the same as that shown in Fig. 3, excepting only that the drain board is omitted and the splash-back 20a is shortened by the omission of the drain board.

25 In the constructions shown in Figs. 2, 3 and 4 the ledge formation and the seamless merger of the roll ends with the splash back is the same as that shown in the remaining figures of the drawing.

30 In the foregoing description, certain terms have been utilized for brevity, clearness and understanding; but no unnecessary limitations are to be implied therefrom or from the use of such words in the claims; and such terms are intended 35 to be broadly construed, as follows:—

The word "sink" used herein and in the claims is intended to include sinks, wash basins, wash bowls and the like; the word "sheet metal" is intended to include sheet and plate metal of the 40 desired or necessary gauge; the words "rolled rim" are not intended to imply arcuately shaped rims since the rims may have any desired shape and may terminate with either shallow or deep skirts, as shown in the drawing; the word "S-shaped" used in referring to the cross section of 45 the ledge, is intended to include any reversely bent or sinuously curved ledge formation which accomplishes the purposes of the present invention; and the words "enamel coated" are intended to refer to and include coatings other than 50 vitreous enamel coatings, which may have similar characteristics to enamel coatings, and the words "enamel coated" are likewise intended to include materials such as stainless steel and the like, which may have characteristics in use for the 55 purposes of the present invention the same or similar to enamel coated sheet metal.

I claim:—

60 1. In an enamel coated sheet metal sink having a fluid receiving bowl with substantially upright side walls terminating in a rolled rim and in an upright splash-back all formed integrally from a single sheet of metal; a stiffening ledge substantially S-shaped in cross section formed between and merging into the bowl and splash-back to provide an offset thereat.

65 2. In an enamel coated sheet metal sink having a fluid receiving bowl and an adjacent drain board terminating in a rolled rim and in an upright splash-back all formed integrally from a single sheet of metal; a stiffening ledge substantially S-shaped in cross section formed between and merging into the bowl and splash-back to provide an offset thereat, and a portion of said ledge ex-

tending between and merging into the drain board and splash-back.

3. In an enamel coated sheet metal sink having a substantially rectangular fluid receiving bowl with substantially vertical side walls terminating in a rolled rim and in a splash-back lying in an upright plane all formed integrally from a single sheet of metal; a laterally continuous ledge substantially S-shaped in cross section formed at the top of one bowl side wall parallel with said side 10 wall to offset the plane of said bowl side wall from the plane of the splash-back.

4. In an enamel coated sheet metal sink having a fluid receiving bowl terminating in a rolled rim and in an upright splash-back all formed integrally from a single sheet of metal; a stiffening ledge substantially S-shaped in cross section formed between and merging into the bowl and splash-back to provide an offset thereat, the rolled rim surrounding the front and sides of said bowl 15 20 and the ends thereof terminating at and merging into said splash-back at the ends of said ledge, and the places of merger between the ends of the rolled rim and ledge and the splash-back being seamless.

25 5. In an enamel coated sheet metal sink having a fluid receiving bowl and an adjacent drain board terminating in a rolled rim and in an upright splash-back all formed integrally from a single sheet of metal; a stiffening ledge substantially S-shaped in cross section formed between and merging into the bowl and splash-back to provide an offset thereat, a portion of said ledge extending between and merging into the drain board and splash-back, the drain board sloping downward 30 35 toward said bowl and being spaced below the plane of the upper portion of the rolled rim, the rolled rim surrounding the front and sides of said bowl and drain board and the ends thereof terminating at and merging into said splash-back, and the places of merger between the ends of the rolled rim and the splash-back being seamless.

6. In an enamel coated sheet metal sink having a substantially rectangular fluid receiving bowl with substantially vertical front, rear and side 40 45 walls terminating in a rolled rim and in a splash-back lying in an upright plane all formed integrally from a single sheet of metal; a laterally continuous ledge substantially S-shaped in cross section formed at the top of the rear bowl wall 50 parallel with the same to offset the plane of said rear bowl wall from the plane of the splash-back, the rolled rim integrally surrounding the front and sides of said bowl and the ends thereof terminating at and merging into said splash-back, the places of merger between the ends of the rolled rim and the splash-back being seamless, and a depending skirt formed integrally in continuation of said rolled rim.

7. In an enamel coated sheet metal sink having a fluid receiving bowl terminating in a rolled rim and in an upright splash-back all formed integrally from a single sheet of metal; a continuous stiffening ledge formed between the bowl and splash-back to offset the splash-back from the 65 rear wall of the bowl, the rolled rim surrounding the front and sides of said bowl and the ends thereof terminating at and merging into said splash-back, and the line of intersection between the ledge and splash-back lying in the plane of 70 the upper portion of the rolled rim.

8. In an enamel coated sheet metal sink having a fluid receiving bowl terminating in a rolled rim and in an upright splash-back all formed integrally from a single sheet of metal; a continuous 75

stiffening ledge formed between the bowl and splash-back to offset the splash-back from the rear wall of the bowl, the rolled rim surrounding the front and sides of said bowl and the ends thereof terminating at and merging into said splash-back, the line of intersection between the ledge and splash-back lying in the plane of the upper portion of the rolled rim and terminating at the places of merger between the ends of the 10 rolled rim and splash-back, and the places of merger between the ends of the rolled rim and splash-back being seamless.

9. In a sheet metal sink having a fluid receiving bowl with substantially upright side walls terminating in a rolled rim and in an upright splash-back all formed integrally from a single sheet of metal; a stiffening ledge formed between and merging into the bowl and splash-back and slop-

ing rearwardly upwardly from the bowl to the splash-back to provide an offset thereat.

10. In a sheet metal sink having a substantially rectangular fluid receiving bowl terminating in a turned rim formed as a part of a depending skirt 5 extending around three sides of the bowl, said sink also having an upright splash-back and being formed from a single sheet of metal; the upright back wall of the bowl terminating below the plane of the upper edge of the rim, the splash-back 10 terminating substantially at the plane of the upper edge of the rim and offset rearwardly from the plane of said back wall, and a continuous sloping ledge seamlessly joining said back wall and said splash-back, the line of intersection between the ledge and splash-back lying in the plane of the upper edge of said rim.

JACQUES STANITZ.
